Patented Feb. 19, 1918.

UNITED STATES PATENT OFFICE.

CHARLES L. EIDLITZ, OF NEW YORK, N. Y.

MOUNT FOR POSTERS.

1,256,993.

Specification of Letters Patent. Patented Feb. 19, 1918.

Application filed March 10, 1916. Serial No. 83,245.

To all whom it may concern:

Be it known that I, CHARLES L. EIDLITZ, a citizen of the United States, residing at the city of New York, in the borough of 5 Manhattan and State of New York, have invented certain new and useful Improvements in Mounts for Posters, of which the following is a full, clear, and exact description.

This invention relates to mounts for advertising posters, pictures and the like.

The object of the invention is to provide a mount which is of a simple and cheap construction and which may be quickly and readily assembled by any one without the 15 use of tools.

The mount is constructed from angle strips stamped out of sheet metal, which strips form the side pieces of the frame. These strips may form an integral structure 20 or each side piece may constitute a separate part. To secure two side pieces together where they do not provide an integral structure right angled corner strips may be fitted on the inside or outside of the side pieces. 25 Ears are formed upon the side pieces or upon the corner piece. Some of these ears are bent around the other part while others pass through slots in the same to form a rigid joint between the side and corner 30 pieces. If the angle strips forming side pieces of the frame are made integral only one corner piece is necessary, but where the four side pieces of the frame are separate a corresponding number of corner pieces are 35 utilized. If inside corner pieces are used the invention also consists in providing these pieces with ears which are arranged to engage a picture or poster of slightly smaller size than the frame and hold it correctly positioned within the frame.

In the accompanying drawings,

Figure 1 shows one type of frame constructed in accordance with the principles of my invention;

Fig. 2 is a section through the frame upon the section line shown in Fig. 1;

Fig. 3 shows a frame of a somewhat different construction, only one corner of the frame, however, being shown;

Fig. 4 shows the corner piece illustrated in Fig. 3, before assembly, and

Fig. 5 shows an inside corner piece provided with additional means for holding a picture or other sheet in place.

In the frame illustrated in Fig. 1, all of the side pieces of the frame are integral and

are formed from an angle strip stamped from sheet metal, one of the legs of the strip, which is designated 1, forming the body of the frame, and the other leg, which is designated 2, forming the flange which surrounds the face of the picture or poster, not shown.

The blank from which the frame is constructed comprises a straight strip which is cut away at suitable intervals corresponding to the lengths of the sides of the frame to provide V-shaped recesses. The straight strip is thereafter bent into rectangular forms, as shown in Fig. 1, when the edges of the V-shaped recesses will abut each other 70 and form miter joints at the corners of the frame. At one corner of the frame the free ends of the strip will abut each other and these ends are secured together by means of a suitable corner piece 5 which comprises a 75 right angled angle strip stamped from a suitable piece of sheet metal. The corner piece fits inside of the abutting ends of the angle strips and is secured in place by ears or lugs 7 which, before the corner piece is 80 fastened in place, project from the body 1 of the frame adjacent the abutting ends thereof and are thereafter bent over upon the corner pieces and hold them against the angle strips. Lugs 8 are also provided by 85 stamping U-shaped slots in the body part 1 of the frame adjacent the ends, which lugs are passed through slots 8' in the corner piece and are then bent down upon the same, which will prevent the angle strips or side 90 pieces of the frame from being pulled laterally away from the corner pieces and will, with the other bent ears 7 before mentioned, rigidly secure the corner piece and ends of the frame together so that a rigid rectangular 95 frame is produced. The construction is a simple one to assemble since the ears 7 and 8 are made integral with the frame pieces and may be bent over upon the corner piece and inserted through the slots in the same 100 without the use of any tools. An advantage arising from this fact is that the picture or poster may be shipped unmounted, together with the frame, which may thereafter be assembled by the person receiving the same.

If desired, an outside corner piece, instead of an inside corner piece, may be provided, in which instance it is preferable to provide the lugs or ears upon the corner piece instead of upon the frame pieces. Such a 110 construction is shown in Figs. 3 and 4, the corner pieces being of similar construction

to that shown in Fig. 1, except that it is of sufficient size to fit outside of the abutting ends of the frame piece and is provided with lugs 9 and 10. The flanges 2 of the frame pieces should be provided with slots 10' through which the lugs 10 are adapted to pass. To assemble the frame the corner pieces are placed over the abutting ends of the frame pieces and the lugs and ears bent down over the same, as described, and since the lugs 10 pass through the slots 10' in the frame it will securely anchor the ends of the frame together, and together with the bent-over ears 9, secure the corner piece to the frame pieces so that a rigid construction is obtained.

In Fig. 5 an inside corner piece is shown which is similar to the one shown in Fig. 1, with the exception that it is provided with additional ears 11 which are adapted to be bent as shown in this view, to provide retaining means for holding a picture or poster of slightly less size than the frame, securely in place therein. The provision of these additional ears will not, however, prevent the corner piece from being used in the manner shown in Fig. 1, since unless the ears are bent as shown in Fig. 5, they will remain parallel and form a part of one of the faces of the corner piece.

As is obvious, the side pieces of the frame should be provided with prongs 12 which are adapted to be bent down upon the rear face of the picture after it has been inserted in the frame to securely hold it in place. These prongs are illustrated in connection with Fig. 3 but the frame shown in Fig. 1 can also be provided with the same if it is found

desirable, such prongs being well known in the art and forming no part of the invention.

I claim:

1. In a frame, two abutting angle strips forming two of the side pieces of the frame, a corner piece at the abutting ends of said strips, ears formed on some of said parts and slots in other of said parts, some of said ears of said parts being bent over said other parts and other of said ears passing through said slots and then being bent over said other parts.

2. In a frame, two angle strips forming two of the side pieces of the frame, a corner piece comprising a right angled angle piece fitting over the ends of the side pieces, said side and corner pieces having slots and ears formed therein, said ears passing through said slots and being bent over to anchor said side pieces to said corner piece, and other ears carried by some of said pieces bent over the edges of the other of said pieces.

3. A corner piece for picture frames comprising two angle strips disposed at right angles to each other and forming the corner of the frame, said angle strips having ears cut in one leg of each of the angle strips which are adapted to be bent up in spaced relation to the other leg of the angle piece to retain a sheet of material of less size than the frame in place therein.

In witness whereof, I subscribe my signature, in the presence of two witnesses.

CHAS. L. EIDLITZ.

Witnesses:

WALDO M. CHAPIN,
JULE E. ZELENKO.
